PACKAGED CLOTHING ARTICLE FOR FORMING A HALTER, TURBAN, SCARF OR THE LIKE

Harold Chesner, 255 Ardmore Ave.,
Staten Island, N.Y. 10314

Filed Sept. 30, 1974, Ser. No. 510,410

Term of patent 14 years

Int. Cl. D9—03

U.S. Cl. D9—193

FIG.1

FIG.5

FIG. 1 is a front elevational view of a packaged clothing article for forming a halter, turban, scarf or the like, showing my new design;

FIG. 2 is a right side elevational view;

FIG. 3 is a fragmented left side elevational view of a top portion thereof, the remaining unshown bottom portion being a mirror image of the corresponding bottom portion shown in FIG. 2;

FIG. 4 is a rear elevational view; and

FIG. 5 is a sectional view along line 4—4 of FIG. 4.

I claim:

The ornamental design for a packaged clothing article for forming a halter, turban, scarf or the like, substantially as shown and described.
